D. DOCTORS

Des. 105,846

HALTER OR SIMILAR ARTICLE
Filed April 13, 1936

FIG. 1

FIG. 2

INVENTOR.
DOROTHEA DOCTORS
BY Maxwell E. Sparrow
ATTORNEY.

UNITED STATES PATENT OFFICE

105,846

DESIGN FOR A HALTER OR SIMILAR ARTICLE

Dorothea Doctors, New York, N. Y., assignor, by mesne assignments, to Dorothea Doctors and Sidney A. Fox, both of New York, N. Y., copartners, trading under the firm name and style of "Dorothea Doctors"

Application April 13, 1936, Serial No. 62,091

Term of patent 14 years

To all whom it may concern:

Be it known that I, Dorothea Doctors, a citizen of the United States, residing in the county, city, and State of New York, have invented a new,
original, and ornamental Design for a Halter or Similar Article, of which the following is a specification, reference being made to the accompanying drawing, forming a part thereof.

Fig. 1 is a front view of a halter or similar article embodying the invention.

Fig. 2 is a rear view of the halter or similar article embodying the invention.

I claim:

The ornamental design for a halter or similar article substantially as shown.
